MAGNETRON CATHODE STRUCTURES

René Zwobada, Enrico Piatte, Jacques Beal, and Remi Juillerat, all of Paris, France, assignors to Societe Lignes Telegraphiques et Telephoniques, Paris, France, a joint-stock company of France

Filed May 25, 1961, Ser. No. 126,370

Claims priority, application France, June 14, 1960, 829,880; Oct. 31, 1960, 842,663; Apr. 27, 1961, 860,263

6 Claims. (Cl. 313—37)

The invention relates to improvements in high frequency, high power magnetrons and bears especially on the tube structure. As mentioned in French Patent No. 1,104,932 of May 19, 1954, the main problem in magnetron manufacture is precise positioning of the cathode with respect to the anode block. In the above mentioned patent is described a magnetron structure designed in order to make cathode centering easier during tube manufacture and to reduce misalignment which might occur during the tube life. According to the above mentioned invention, cathode centering with respect to the anode block is visually controlled during tube assembly. An especially designed supporting part is provided to allow setting of the pole piece without requiring any further high temperature heating which may affect cathode centering.

It has been described in French Patent No. 1,200,355 of April 23, 1958, the particular problems to be solved in manufacturing a high power, very high frequency magnetron. One of the main difficulties lies in eliminating a large quantity of heat through the cathode structure, combined with the necessary heating of the cathode by an external source in order to bring the cathode coating at the right temperature for initiating oscillation. The cathode structure which is described in the last mentioned patent is a cylindrical unit which supports at one end the heater and, at the other end, the cooling device, the emissive coating being located inbetween on the cylinder. Such a structure has proved to be very reliable and to provide a long lifetime. As shown in the drawing appended to this patent, the cathode structure is only supported at one end, the heater end is not connected to any solid part of the tube envelope. This design will not provide for sufficient mechanical stability when the tube is submitted to high vibration or acceleration since conditions may happen when the cathode structure will vibrate thereby disturbing normal tube operation.

In order to improve the tube ruggedness, it has been proposed to fix the cathode cylinder at both ends. Such a design is very difficult to manufacture. Indeed, during the tube life, the cathode assembly is submitted to numerous thermal cycles which cause alternate expansions and contractions and it is therefore very difficult to fix the cathode structure at both ends to parts sufficiently solid to provide for mechanical rigidity without excessive stresses being developed in the cathode structure. On the other hand, the unitary cathode structure is metallic and the end to be housed will be set at very high potential during operation. The design of the engaging part is therefore difficult.

The object of the present invention consists in a magnetron structure with a mechanical stability improved over the structure described in Patent 1,200,355 but still presenting the same advantages as such structure especially with respect to evacuation of heat from the cathode structure when the magnetron is operated at high power level.

Another object of the invention consists in a cathode structure which allows for high precision centering of the cathode in the anode block without requiring a specially

2

designed part to allow for the setting of the second pole-piece.

It is an object of the invention to provide for a magnetron structure in which both the cathode hat diameters may be larger than the anode cavity diameter.

It is an object of the present invention to provide means for eliminating any stress which may occur due to thermal expansion of the cathode structure during tube operation.

It is another object of the invention to provide for means to adjust the cathode position with respect to the anode block after the tube is assembled.

It is an object of the invention to allow for the reduction of the number of dielectric to metal seals in the tube envelope.

15 The present invention will be readily understood by reference to the following description and the appended drawings which represent four embodiments of magnetron structure given as illustration of the invention without intention of covering the whole scope of the invention.

20 FIGURE 1 shows the complete tube structure incorporating the cathode shown at FIGURE 2B.

FIGURES 2A and 2B show two cathode structures with slidable engagement of the cathode parts.

25 FIGURE 2C is a sectional view along the lines X-X' of FIGURE 2B.

FIGURE 3 shows a tube structure according to the invention with a welded cathode structure.

30 FIGURE 4 shows a complete tube structure incorporating means for adjusting cathode centering after tube assembly.

The cylindrical cathode structure 1 consists of a lower part 1' and an upper part 1". Emissive coating 2 is deposited near the upper end of 1' which is terminated at one end by a centering finger 3 and connected at the other end to the cooling device 4 of the type described in

35 abovementioned French Patent No. 1,200,355. Such device is designed for liquid cooling. Any other type of cooling device such as a set of blades for air cooling may be used. The anode block is shown at 5. It is brazed or welded to pole pieces 6' and 6" as is well known. The lower part 1' of the cathode structure is fixed to the lower pole piece 6' by means of the dielectric ring 7 which is sealed or brazed to pole piece 6' and to 1' by metallic sealing rings 7' and 7". Cathode part 1" houses the

40 heater 14 and is terminated at its lower end by a centering flange 10-9 (cf. FIGURE 2B). It is positioned with respect to upper pole piece 6" by the dielectric ring 13 sealed or brazed by means of metal sealing rings 13' and 13". Part 1" consists mainly of flange 9-10, cylinder 11

50 and tube 12. It can be centered with precision with respect to anode block 5 under visual control from the lower part of the structure. It is then assembled by sealing ring 13 to 13' and 13" and brazing 13" to the upper pole piece 6" and ring 13' to tube 12 through L profiled ring 12'. Filament 14 is connected at its lower end 15 to flange 10 and at the upper end 16 to the annular output 17 through stem 17'. Filament connection is electrically insulated from the cathode by the dielectric ring 18. The tube envelope is completed by sealing on the insulating

55 glass cup 19 which is the exhaust connection. Heater current flows from 17 to stem 17' which is in conductive relationship with the upper end of filament 14. The second filament connection may be taken at 12 or at the lower end of the cathode structure. It is also the cathode 60 D.C. connection. Cylinder 11 acts as a thermal screen between filament 14 and the tube envelope (13"-13', etc.).

When part 1" is positioned, centering finger 3 of the lower cathode part is engaged in the flange 10 the internal face in which has been high precision machined. In order to make assembly easier, the lower part of internal face of flange 10 is round and centering finger 3

is slightly conical. Finger 3 is free to slide in flange 10 to take over the thermal expansion of the cathode structure. In order to reduce friction of finger 3 against flange 10, longitudinal grooves are machined in finger 3 so as to reduce the bearing surface between 3 and 10. Such grooves could also be machined in flange 10 instead of finger 3. Cathode unit 1 is made of molybdenum and so is flange 10. Cathode hats are treated so as to reduce emissivity as is well known.

FIGURE 2A shows details of the engaging terminations of parts 1' and 1'' of an embodiment slightly different from FIGURE 1. Lower part 1' is a hollow cylinder bearing cathode hats 8 and 9 which may be either solid with the cylinder or fastened to it by welding or brazing. Emissive coating 2 is deposited between the hats. Part 1' is terminated by centering finger 3. The lower end of upper part 1'' consists of centering flange 10 supported by cylinder 11 which acts as a thermal screen between filament 14 and the tube envelope.

FIGURE 2B shows details of the engagement between parts 1' and 1'' of the cathode corresponding to the embodiment in FIGURE 1. Flange 10 acts as the second cathode hat while performing also its centering function. In this embodiment, flange 10 is made of a non-emissive material such for example as molybdenum carbide, tungsten carbide, tantalum carbide, or other metallic carbides which as is well known are non-emissive at the temperatures encountered in the operation of tubes of this type. Centering finger 3 is preferably made of the same material as flange 10. It is therefore no longer unitary with the cathode part 1'. Finger 3 is tightened to cathode structure 1' according to any method known per se (brazing, welding, etc . . .).

FIGURE 2C shows the cathode structure as seen in a plane perpendicular to axis of the structure, the trace of which appears as X-X' on FIGURE 2B. The upper cathode part 1' engages in finger 3, the external face of which is grooved as seen at 3' in order to reduce the bearing surface between finger 3 and centering flange 10 acting also as one of the cathode hats 9.

Diameter of the cathode hats 8 and 9 (or 10 according to the embodiment) may be chosen as large as suitable to optimize the operating conditions of the magnetron. Indeed, it is no longer limited by the internal diameter of the anode cavity since assembly does not require passing the cathode hats through the anode cavity.

Cylinder 11 operates as a thermal screen between filament 14 and the tube envelope. It is heated at a rather high temperature and is preferably made of a material which will absorb the gas which may be liberated during tube operation due to electron bombardment or desorption by the anode or envelope walls. In order to simplify the drawing the R.F. chokes which should be provided along cylinder 11 have been omitted. They are necessary in order to prevent any loss of high frequency energy along the cathode structure which should be restricted to the volume of the cavities between the cathode and the anode block 5.

The thickness of cylinder 11 is chosen in order to allow a sufficient elasticity of this cylindrical part so as to allow it to be distorted under the control of centering adjustment device not represented in FIGURE 1 which is operated as will be explained in relationship in FIGURE 4 in order to provide final adjustment of the cathode position with respect to the anode block.

FIGURE 3 represents the same tube structure in which free thermal expansion of the cathode is allowed by means external to the cathode structure and located on the tube envelope, that is at a point which is kept cool even during tube operation. The parts common to the structures described on FIGURES 1 and 3 bear the same reference numbers.

During tube assembly, centering finger 3 of part 1' is rigidly fixed in part 1'' by brazing or welding to flange 10. The upper end of cylinder 11 is connected to a pair

5 of flanges 21 and 22. These flanges are made of a metallic sheet sufficiently thin to allow resilient deformation of the two flanges which constitute a mobile parallelogram allowing free translation of the whole cathode structure along a direction parallel to its axis. The parallelogram defined by the radial flanges 21-22 prevents any radial displacement of cylinder 11 therefore preserving cathode concentricity. Flanges 10, 21, 22, cylinder 11 and the centering finger 3 are machined on the same tool fixture so as to allow for the best concentricity which may be obtained. Tube assembly is made as follows: flanges 10, 21 and 22 are welded to the upper part 1'' subassembly which consists of flange 10, cylinder 11, filament connection seal 18 and the exhaust connection 19 (shown sealed in the figure). The sub-assembly 10 is then machined another time to obtain a high precision inside face for flange 10. It is sealed at 13' and 13'' to the anode sub-assembly which comprises 5-6-13'-13-13' and 7-7-7'. The lower part 1' of the cathode structure 20 is mounted and finger 3 is engaged in flange 10. Welding is performed between 3 and 10 and then the envelope is completed by sealing 7'' to 1'.

FIGURE 4 shows an embodiment of the invention in which cathode positioning with respect to the anode block may be adjusted after assembly of the tube. As shown in the previous figures, the cathode structure comprises a lower part 1' associated with the cooling device 4 and terminated at its upper end by centering finger 3. The upper part 1'' of the cathode structure houses the heater 14 and consists mainly of cylinder 11 which acts as a thermal screen for the heater and as a support for centering flange 10 in which centering finger 3 is fixed by screwing or any other method known per se. Cylinder 11 is terminated by a dielectric wafer 40 which provides for the electric insulation of cylinder 11 with respect to the upper part of the tube envelope. It is therefore possible to use the upper end of the cathode structure consisting of metallic tube 12 as one heater output without need of insulating seal 18 instead of output 17 of FIGURES 1 and 3. Free expansion of the cathode structure along its axis is allowed by the elasticity of one Z shaped thin metallic flange 22 welded to the cathode structure at one end and to the anode block at the other by means of the tube envelope (12''-13'-13-13''-6'').

Adjustment of cathode position is manually controlled by means of the device 31 to 36 associated with the lower part 1' of a cathode structure. This adjustment is obtained by deformation of a thin walled resilient cylinder 31 connected at its upper end to the cathode structure 1' by means of a solid ring 35 and welded at its lower end to a rigid metallic ring 34 of the tube envelope. 34 bears several drilled holes in which are introduced control screws such as 32 and 33, the end of which bears against cylinder 36 which belongs to the cathode structure 1' and surrounds the cooling device 4. As will be readily understood by screwing or unscrewing screws 32, 33, etc., the lower end of cylinder 31 is displaced with respect to cathode structure 1'. The upper end of cylinder 31 tends also to move thereby carrying along 1'. The whole cathode structure tends to rotate, the center of rotation being located at the seal between the cathode structure and flange 22'. This displacement of the whole cathode structure will change the position of emissive coating 2 in the anode cavity.

65 Tube assembly is carried on as follows: assembly of the anode sub-assembly consisting of anode block 5, pole pieces 6'-6'', and seals 7 and 13 (by means of 7' and 13'') carrying metal collar 13'. collar 7'' is sealed to 7. the upper part 1'' of the cathode is centered with respect to the anode sub-assembly and sealed. It consists mainly of cylinder 12—dilatation flange 22'—solid ring 21—wafer 40, cylinder 11 threaded centering flange 10 and the filament sub-assembly. Lower part 1' of the cathode bears a centering finger 3 which is

threaded and is screwed in flange 10. Solid ring 21' slides along collar 13' during this operation. the tube envelope is completed by brazing collar 13' to ring 21'.

We claim:

1. A magnetron comprising in combination: an elongated cathode structure including first and second parts; a filamentary heater housed within said first part; means connected to said second part affording connection of a cooling means thereto; an emissive coating on said structure adjacent said first part; at least one cathode hat integral with said second part; an apertured anode surrounding at least the emissive portion of said structure, the aperture being of less diameter than the diameter of said hat; pole pieces connected to said anode; and envelope means connected between said cathode structure and said pole pieces.

2. The combination defined by claim 1 in which two cathode hats are integral with said cathode structure, one positioned on either side of said emissive coating.

3. The combination defined by claim 2 in which said envelope means includes resilient portions connected between one of said cathode parts and said pole pieces.

4. A magnetron comprising in combination: an elongated cathode structure including first and second parts; a filament heater housed within said first part; means affording connection of a cooling device to said second part; an emissive coating on said second part adjacent said first part; a cathode hat on said second part on one side of said emissive coating; a centering finger on said second part on the other side of said coating and extending longitudinally of said second part; a centering flange terminating said first cathode part adjacent said second cathode part; an apertured anode surrounding said emis-

sive coating, the aperture therein being of less diameter than either said hat or flange external diameters; pole pieces connected to said anode; and envelope means connected between both said cathode parts and said pole pieces.

5. A magnetron comprising in combination: an elongated cathode structure including first and second parts; a filament heater housed within said first part; means affording connection of a cooling device to said second part; an emissive coating on said second part adjacent said first part; a pair of cathode hats, one on each side of said emissive coating; an apertured anode surrounding said emissive coating, the aperture therein being of less diameter than said cathode hats; pole pieces connected to said apertured anode; envelope means connected between each of said cathode parts, said means including a resilient cylinder connected between said second cathode part and said pole pieces; and adjustment means contacting said second cathode part and said resilient cylinder.

10 15 20 6. The combination defined by claim 5 and further including at least one resilient part connected between said first cathode part and said pole pieces.
